Primary Examiner—Stella Reid**CLAIM**

The ornamental design of a body aligner, as shown and described.

DESCRIPTION

FIG. 1 is a front elevational view of a body aligner embodying the design of the present invention;
FIG. 2 is a right side elevational view thereof;
FIG. 3 is a bottom end elevational view thereof, which is identical in appearance to the reverse of the top elevational view thereof;
FIG. 4 is a back elevational view thereof; and,
FIG. 5 is a left side elevational view thereof.
